UNITED STATES PATENT OFFICE.

HERBERT L. NELKE, OF PHILADELPHIA, PENNSYLVANIA.

PROCESS OF MANUFACTURING KNITTED FABRICS.

No. 893,356.

Specification of Letters Patent.

Patented July 14, 1908.

Application filed March 11, 1908. Serial No. 420,423.

To all whom it may concern:

Be it known that I, HERBERT L. NELKE, a citizen of the United States, residing in Philadelphia, Pennsylvania, have invented certain Improvements in Processes of Manufacturing Knitted Fabrics, of which the following is a specification.

My invention relates to the manufacture of neckwear and consists of a method of producing the same from a seamless cylindrical knitted fabric.

One object of my invention is to cut a fabric of the above described nature so that a strip of single thickness having opposite sides parallel and whose length is greater than that of the cylinder from which it is cut will result.

Another object is to so cut the fabric that this strip will have its courses of loops running obliquely, or similar to twill lines in woven fabric.

In the drawings Figure 1, is a diagrammatic perspective view of a seamless knitted fabric; Fig. 2, is a perspective view of the tube flattened and showing a templet in position; Figs. 3 and 4, show the fabric marked for cutting; Fig. 5, shows the fabric after having been cut and ready for unwrapping; Fig. 6 is a view of the fabric as it is when cut and unwrapped; and Fig. 7 shows a strip cut from the fabric of sufficient width for the production of neckties.

Neckwear of knitted fabric has been made upon machines designed for underwear, the fabric being cut in strips, shaped and sewed, or it has been made upon machines which produce tubular work of small diameter and seamless such as a "Lamb" knitter. The coming style in woven neckwear is one in which the stripes run obliquely to the length thereof and it is one of the objects of my invention to produce the same effect in a scarf, necktie or other article made from a machine knitted fabric.

Referring to the drawings, 1 represents a seamless tubular knitted fabric, flattened as shown in Fig. 2. A templet 2, in the form of a 45° triangle in the present instance, whose altitude is equal to the width of the flattened fabric, is placed upon the fabric, as clearly shown in Fig. 2, so that one angle of 45° in the present instance touches a corner of the fabric and the base 3 of the angle is flush with the running edge of the fabric. A line *a* is then scribed along one side 4 of the triangle and a mark made at *x* on the side 5 of the triangle. The triangle is then

moved over the fabric until the angle that was at the corner of the fabric comes over the mark *x*, then another line *c* is scribed on the fabric through the point *x* and is parallel to the line *a*. This operation is repeated throughout the length of the fabric; the line being made obliquely to the courses 6 of the fabric, which are shown by the lining in the several views of the drawing. The fabric is then turned over, presenting its other face to the operator and the lines *b*, *d*, *f*, are drawn so as to connect with the lines *a*, *c*, *e*, at the edge of the fabric, as shown in Figs. 3 and 4. The operator then cuts on the lines *a*, *c*, *e*, *b*, *d* and *f* but only through a single thickness of the fabric. The fabric is then unwound or unlapped and produces the strip of single thickness, as shown in Fig. 6, and the courses of the loops 6 are oblique to the running edge.

If a fabric of narrow width is desired, such as is employed in the manufacture of neckties, a strip may be cut such as is shown in Fig. 7, which I have shown in this case of sufficient length to produce two neckties; the only waste being the triangular sections at each end, as shown by dotted lines in Fig. 7. The strip may then be cut in proper lengths, shaped and finished in the usual manner.

While I have shown in the accompanying drawing a movable templet and markings made upon the fabric, I do not hold myself to this particular arrangement but may have the templet stationary *i. e.* in the form of a table, bench, etc. and markings upon the same spaced at given distances apart and the angle cutting determined by said markings.

It will be understood that while the invention is particularly adapted for the manufacture of neckties, it may be used for other purposes without departing from my invention.

I claim:—

1. The process herein described of producing a knitted fabric in which the loops are arranged obliquely to the length of the fabric, the same consisting in knitting a tubular fabric, marking lines on opposite sides of the fabric, the lines on one side joining the lines on the opposite side, cutting the single fabric on these lines so as to produce a length of single fabric with the loops running obliquely to the length of the line of the fabric, substantially as described.

2. The process herein described of producing a knitted fabric in which the loops are arranged obliquely to the longitudinal line of the fabric, the same consisting in knitting a tube, flattening the tube, scoring one side of the flattened tube on lines at an angle of 45° spaced a given distance apart, and one line being parallel with the other, then turning the fabric over and marking lines at 45° so as to join the other lines, and then cutting the fabric on these lines so as to produce a fabric in which the loops will be arranged at an angle of 45° in respect to the longitudinal line of the fabric, substantially as described.
3. The process herein described of produc-

ing a flat knitted fabric in which the loops are arranged obliquely to the length of the said fabric, said process consisting in knitting a tubular fabric and cutting the single thickness of the fabric on a line diagonal to the line of loops, producing a flat fabric with the loops oblique to the longitudinal line of the fabric.

In testimony whereof, I have signed my name to this specification, in the presence of two subscribing witnesses.

HERBERT L. NELKE.
